UNITED STATES PATENT OFFICE

2,659,991

NAME OR DIRECTORY CARD HOLDER

Daniel H. Strayer, Los Angeles, Calif.

Application March 15, 1950, Serial No. 149,842

1 Claim. (Cl. 40—10)

1

My invention relates to holders for name and business directory cards, either printed or written, and which are particularly designed for use on the doors of residences, apartments, offices and the like; also on business desks, filing cabinets, storage drawers, and shelves, or wherever a brief identification or information card or panel is required or desirable.

The principal object of my invention is, to provide a simple, practical, and inexpensive holder in the form of a compact attractive plate having a narrow slot or pocket for reception of a directory or information bearing card and the construction of which holder is such as to enable the inserted member to be readily placed in or removed therefrom and when properly enclosed within said holder, to be effectively protected against dust, moisture and finger marks.

With the foregoing and other objects in view, my invention consists in certain novel features of construction of parts which will be herein-after more fully described and claimed, and illustrated in the accompanying drawing, in which:

Fig. 1 is a front elevational view of a card holder constructed in accordance with my invention.

Fig. 2 is a horizontal section taken on the line 2—2 of Fig. 1.

Fig. 3 is a vertical section taken on the line 3—3 of Fig. 1.

Fig. 4 is a detail vertical section of the upper right-hand corner of the holder.

Fig. 5 is an enlarged horizontal section taken on the line 5—5 of Fig. 1.

Fig. 6 is a horizontal section through the central portion of one of the holders' end-closing members.

Referring by numerals to the accompanying drawing, which illustrates a preferred embodiment of my invention, 10 designates the body of the holder which is in the form of a plate of suitable transparent material; for instance, clear plastics, and extending lengthwise through said plate is a narrow slot 11 adapted to receive a card C, bearing on its front face, printed or written matter, or information.

Formed through the upper and lower portions of plate 10, above slot 11, are apertures 12, adapted to receive screws 13, which secure the plate to a base, such as a door, desk, shelf, or the like. To close the open ends of slot 11, substantially channel-shaped members composed of semicircular bodies 14 and curved flanges 15 are slidably mounted on the ends of plate 10, with

2

the edges of said flanges occupying vertical grooves 16, formed in the front and rear faces of said plate adjacent and parallel with its ends, and with the flat inner faces 17 of bodies 14 fitting snugly against the ends of the plate.

To maintain the slot end closures in proper position on the ends of the plate, small horizontal plates 18 integral with the upper ends of bodies 14 and flanges 15, occupy rectangular notches 19 formed in upper corners of plate 10, between grooves 16 (see Fig. 4).

In some instances it may be found desirable to permanently close slot 11 at one end of the plate and employ the sliding closure, at the other end only.

The end closures just described are capable of being quickly applied to or removed from the card holding plate, are effective in preventing the ingress of moisture and dust into the card-containing slot 11 and they may be made from plastics, metal, or the like, of distinctive color from the plate, and thereby enhance decorative appearance thereof.

Thus it will be seen that I have provided a name or directory card holder which is simple in structure, inexpensive of manufacture, applicable for a wide variety of uses, and very effective in performing the functions for which it is intended.

Minor changes in the size, form and construction of my improved card holder may be made and substituted for those herein shown and described, without departing from the spirit of the invention, the scope of which is set forth in the appended claim.

I claim as my invention:

In a name or directory card holder, the combination with a piece plate of transparent material, provided with a slot open at its ends for the reception of a card bearing written or printed matter on its face, which plate is provided at its ends above said slot with inwardly presented horizontal notches, there being vertically disposed grooves formed in the front and rear faces of said plate adjacent and parallel with its ends, the upper ends of which grooves communicate with said horizontal notches, channel shaped end pieces having a length equal to the vertical dimensions of said plate, slidable onto the ends of said plate with the side edges of said channel shape end pieces occupying the grooves in said plate and horizontal plates integral with the upper ends of said channel shaped end pieces which horizontal plates occupy the inwardly presented notches in said plate above the ends

of the slot in said plate to form water and dust
proof joints.

DANIEL H. STRAYER.
